[57] CLAIM

The ornamental design for a container lid, as shown and described.

DESCRIPTION

FIG. 1 is a perspective view of a container lid showing our new design;

FIG. 2 is a top plan view thereof;

FIG. 3 is a side elevational view thereof, the remaining sides being exactly the same;

FIG. 4 is a bottom plan view thereof;

FIG. 5 is an enlarged side elevational view thereof, partially broken away for clarity;

FIG. 6 is a perspective view of a container lid showing a further embodiment of our new design;

FIG. 7 is a top plan view thereof;

FIG. 8 is a side elevational view thereof, the remaining sides being exactly the same;

FIG. 9 is a bottom plan view thereof; and,

FIG. 10 is an enlarged side elevational view thereof, partially broken away for clarity.
